(57) **CLAIM**

The ornamental design for a nesting shopping cart, substantially as shown and described.

DESCRIPTION

FIG. 1 is a right front perspective view of the nesting shopping cart showing an example of our new design; FIG. 2 is an enlarged top view of a nesting shopping cart of FIG. 1;

FIG. 3 is an enlarged front view of the nesting shopping cart of FIG. 1;

FIG. 4 is an enlarged right side view of the nesting shopping cart of FIG. 1, the left side view being the mirror image thereof;

FIG. 5 is an enlarged rear view of the nesting shopping cart of FIG. 1; and,

FIG. 6 is a right rear perspective view of the nesting shopping cart of FIG. 1.

The broken lines in the drawings depict portions of the nesting shopping cart which form no part of the claimed design.

1 Claim, 6 Drawing Sheets
